UNITED STATES PATENT OFFICE.

OAKLEY FLOYD COOPER, OF LOGAN, OHIO.

CUTTER.

Application filed December 2, 1922. Serial No. 604,550.

To all whom it may concern:

Be it known that I, OAKLEY FLOYD COOPER, a citizen of the United States, residing at Logan, in the county of Hocking and State of Ohio, have invented new and useful Improvements in Cutters, of which the following is a specification.

An object of this invention is to produce a machine for cutting lard into blocks of desired sizes and which may be also successfully employed for cutting butter into blocks, meat into strips, etc.

A further object is to produce a machine for this purpose in which the feeding, slitting and cutting mechanism are arranged in timed operation whereby blocks or strips of determined sizes of lard or the like may be obtained.

A further object is to produce a machine for this purpose which shall be characteristic of simplicity in construction, coupled with ease and accuracy in operation.

To the attainment of the foregoing and other objects which will present themselves as the nature of the invention is better understood, reference is to be had to the drawings which accompany and which form part of this application.

In the drawings:—

Figure 1 is a side elevation of the improvement.

Figure 2 is a top plan view thereof.

Figure 3 is a sectional view on the line 3—3 of Figure 2.

Figure 4 is a sectional view on the line 4—4 of Figure 1.

Figure 5 is a sectional view on the line 5—5 of Figure 1.

Figure 6 is a sectional view on the line 6—6 of Figure 2.

As disclosed by the drawings I make use of a substantially rectangular receptacle 1. The receptacle is constructed of material best suited for the purpose designed and has its top, at a suitable distance from its end 2 open. The sides of the receptacle are rounded downwardly to the end 2. Thus the end 2 is of a materially less height than the opposite end 4 of the receptacle, and the opening provided in the receptacle is closed by a hinged door 4 shaped to snugly engage the upper edges of the sides and the end 3 of the said receptacle. The opening closed by the door 4 provides the inlet or mouth

portion of the receptacle and will, herein-after for convenience, be so referred to.

Journaled in suitable openings in the sides of the receptacle, at a determined distance from the closed rear end 3 thereof, there is a shaft 5. The shaft projects through the

sides of the receptacle and has secured on one end thereof a belt wheel 6 designed for use when the machine is operated by power.

On the said end of the shaft there is a crank handle 7 whereby the machine may be manually operated. On the opposite end of the shaft there is fixed a comparatively large toothed wheel 8 which is in mesh with a smaller and wider toothed wheel 9. The

shaft 10 for the toothed wheel 9 is journaled in bearings 11 supported on lugs 12 secured to the bottom at the sides of the receptacle 1. On the shaft 10 there is keyed or otherwise secured a ribbed roller 13 whose upper

surface is received through an opening 14 in the bottom 15 of the receptacle. The surface of the ribbed roller received through the opening 14 is disposed only a slight distance above the inner surface of the bottom wall 15 of the receptacle. Journaled in

bearing openings in the sides of the receptacle 1, in a line with the angularly related shafts 5 and 10 there is a shaft 16 having keyed on one of its ends a toothed wheel 17.

The shaft 16 is preferably removably journaled in its bearings and has removably and preferably adjustably secured thereon any desired number of equi-distantly spaced disk cutters 18. The lower edge of each of the cutters 18 are received in grooves 19

arranged longitudinally in the floor 15 of the receptacle. Between the toothed wheels 9 and 17 there are meshing idlers 20 respectively, one of which engaging the teeth of the wheel 9 and the other the teeth of the wheel 17. The purpose of this arrangement will presently be apparent.

The sides of the receptacle, at a suitable distance above but in a line with the shaft 9 have alining arcuate slots 21 therethrough in each of which there is received a bearing for a shaft 23, and each of said bearings is influenced by a spring 24, whereby the shaft

23 is normally forced downwardly or toward the shaft 10. On the shaft 23 there is keyed a peripherally ribbed roller 25 de-

signed for cooperation with the roller 13. It is between these rollers that the lard fed

through the mouth of the receptacle passes and is forced against the disk cutters 18 so that the same is cut longitudinally.

On the shaft 5 there is loosely journaled a hollow shaft or tube 26 which has its ends extending through the bearing openings in the sides of the receptacle for the said shaft 5. Fixed on the ends of the sleeve 26 there are cam wheels 27, and on the outer face of one of the cam wheels there is a toothed wheel 28 in mesh with one of a pair of toothed idlers 29, the second idler being in mesh with the toothed wheel 17. Also on the sleeve or hollow shaft 26 there is a larger toothed wheel 30 in mesh with one of a train of idlers 31 respectively having stub shafts, similar to the other idlers projecting from one side of the receptacle 1. One of the end idlers is in mesh with a pinion 32 keyed on one end of the shaft 23.

Arranged for vertical reciprocatory movement in the casing 1 there is a transversely disposed knife 33 disposed in a line 25 with an opening 34 in the bottom 15 of the casing, and this opening is surrounded by a trough 35 in which the cut lard is received. On the bottom 15 there is secured an adjustable stop 36 designed for contact by 30 the lard slotted by the rotary knives or disks 18 to hold the lard in a position to be cut by the knife 33. The knife 33 is secured in a head block 37, the said block having lugs 38 that project through vertical opening 39 in the sides of the receptacle. These lugs have passed therethrough rods 40, each of said rods being received through a guide 41 on the outer side of the receptacle and surrounding each rod 40 and exerting 40 a tension between the guide 41 and the lug 38. There is a helical spring 42. The spring is designed to force a roller 43 journaled on the lower angle end 44 of each rod 40 into contacting engagement with the periphery of the cam wheels 27.

Below the mouth, at the front of the receptacle there are secured to the sides thereof blocks 45 which have their upper and downwardly inclined edges provided with 50 spaced curved depressions forming bearings for trunnions on the ends of rollers 46. The lard is fed directly on to the rollers 46 and from thence between the ribbed wheels 25 and 13. The lard is delivered on to the slitting disk cutters against the stop 36, the knife 33 being in elevated position when the lard is thus fed. When the cam wheels pass off of the elevated portions of the cam wheels the springs will force the knives 60 downwardly to position illustrated in Figure 3 of the drawings, so that the lard is cut into blocks and falls into the trough 35. Because of the different sized toothed wheels and the idlers employed, one revolution of the wheel 8 causes the ribbed roll-

ers 13 to make five revolutions and the disk carrying shaft ten revolutions. The second ribbed roller 25 is caused to make five revolutions to every revolution of the wheel 8. The disk knives, by such arrangement run twice as fast as the rollers and the knife will be raised and lowered at every half revolution of said wheels. By employing different sized rollers and by adjusting the disk cutters with respect to each other, as well as adjusting the stop 36, varying lengths of slotted lard may be cut, and also by employing different shaped cams the timed raising and lowering of the knife may be regulated.

It is thought that the foregoing description, when taken in connection with the drawings will fully set forth the construction, operation and advantages of the improvement to those skilled in the art to which such inventions relate, but it is to be understood that the nature of the invention is such as to render the same susceptible to such changes and modifications as fall within the scope of what is claimed.

When the device is employed for cutting meat into thin strips, the reciprocatory knife is held elevated by suitable latching means, and it is, of course, to be understood that idlers of different sizes than those disclosed by the drawings may be employed for cutting the lard into chunks. The desirable sizes of these chunks or blocks being one and one-fourth inches, one and one-half inches, and one and three-fourths inches in length. Also the rollers that feed the lard or meat to the rotary and reciprocatory cutters may be revolved by power, when the machine is so driven or may be hitched to one of the rotary parts of the device and thus revolved when the machine is manually operated.

Having described the invention, I claim:

1. In a device for the purpose set forth, a casing having an inlet mouth, upper and lower longitudinally ribbed rollers journaled in the casing adjacent the mouth, means for adjusting the rollers with respect to each other, disk cutters arranged transversely in the casing to one side of the rollers, means for imparting timed rotary motion to the rollers and to the disk cutters, a vertically movable cutter in the casing spaced from the disk cutters, spring means influencing the cutter to cutting position, and means operated by the actuating means for the rollers and disk cutters for elevating the knife.

2. In a device for the purpose set forth, a casing having an opening providing a mouth, upper and lower rollers journaled in the casing adjacent the mouth thereof, spring means influencing the bearings of one of the rollers, adjusting means for the bearings

of the other roller whereby the rollers may be sustained adjusted with respect to each other, disk cutters arranged transversely in the casing adjacent to the lower roller, said casing having a flanged outlet spaced from the disk cutters, a vertically movable knife arranged transversely in the casing over the outlet therefor, spring means influencing the

knife downwardly to cutting position, cam means for raising the knife to non-cutting position, and means for turning the rollers and disk cutters and raising the knives in timed relation to each other.

In testimony whereof I affix my signature:

OAKLEY FLOYD COOPER.
